UNITED STATES PATENT OFFICE

2,617,234

FLUID DISPENSING APPARATUS

David S. Willson, Muskegon Heights, and Joseph C. Woodford, Spring Lake, Mich., assignors to John Wood Manufacturing Company, Philadelphia, Pa., a corporation of Delaware

Application May 5, 1945, Serial No. 592,178

11 Claims. (Cl. 50—23)

1.

Our invention relates to devices for controlling the supply of air under pressure in pulsations from a source of supply of compressed air to a receiver, for example, to an automobile tire. Our invention includes means to variably predetermine the pressure to which the receiver is to be inflated and to automatically shut off the delivery of air to the receiver when the pressure in the receiver reaches the predetermined pressure.

Our invention relates particularly to safety shut-off means for such devices to prevent inflation in excess of the predetermined set pressure if the inflating valve of the device should become stuck in open position. Our invention is applicable generally to any device of the type described above, and herein as illustrative we have shown and described our invention embodied in the type of fluid dispensing apparatus disclosed in Letters Patent of the United States No. 2,126,693, granted August 9, 1938, to David S. Willson and in Letters Patent of the United States Re. 19,201, granted June 5, 1934, to Albert Penn.

Fig. 1 is a front elevation, partly in section, of fluid dispensing apparatus conveniently embodying our invention.

Fig. 2 is an enlarged vertical sectional view of the safety shut-off means indicated in Fig. 1, and with the safety shut-off valve shown in closed position.

Fig. 3 is a vertical sectional view of the structure shown in Fig. 2, but with the safety shut-off valve shown in open position.

Fig. 4 is an enlarged vertical sectional view of a modified form of safety shut-off means, and with the safety shut-off valve shown in closed position.

Fig. 5 is a vertical sectional view of the structure shown in Fig. 4, but with the safety shut-off valve shown in open position.

Fig. 6 is an enlarged vertical sectional view of another modified form of safety shut-off means, and with the safety shut-off valve shown in closed position.

Fig. 7 is a vertical sectional view of the structure shown in Fig. 6, but with the safety shut-off valve shown in open position.

Referring to Fig. 1; the fluid dispensing apparatus in which we have shown our invention embodied is of a construction which is well known in the art and which is described in structural detail and operation in said Willson Patent No. 2,126,693 and Penn Patent Re. 19,201. A source of air under high pressure, say 125 to 150 pounds per square inch, is connected by suitable piping

5 to the air inlet port 2 formed in the casing 3 which houses the main valve 4 and safety shut-off valve 5; which are described hereinafter in detail. Said casing 3 is conveniently mounted in the wall of the casing 6 by means of nuts 7 and 8 which are in screw threaded engagement, on opposite sides of the wall of the casing 6, with the screw threaded extension 10 of the casing 3. When said valves 4 and 5 are in open position, 10 the compressed air flows through the outlet port 12 and through the conduit 13 to the T-fitting 15. The air passes from the fitting 15 through the conduit 16 to the flexible dispensing hose 17, which carries at its distal end an air chuck 18 of the well known conventional type, including a valve which is maintained closed by air pressure in the hose 17 and which valve is adapted to be opened by the operator pressing the chuck against the ordinary valve stem of an automobile tire.

15 The snap action controlling mechanism for operating said valves 4 and 5 includes the main lever 20 which is fulcrumed at 21 on the base plate 23. The short arm 24 of said lever 20 is in contact with the stud 25 projecting upwardly from a plate 25 which rests upon the flexible diaphragm 26. Said diaphragm 26 is clamped to the base plate 23 by a series of screws 27 which extend through the flange 28 of the cup shaped casing member 30 which contains the air chamber beneath the diaphragm 26; and which air chamber is connected to the T-fitting 15 by the branch 15 which contains a timer valve.

20 When the valves 4 and 5 are opened the conduit leading to the chuck valve 18 is charged with compressed air at substantially the pressure of the supply tank and the diaphragm 26 is uplifted to turn the lever 20 clockwise against the stresses of the spring 32, one end of which is connected 25 to the upper end of the lever 20. The opposite end of the spring 32 is connected to the spring adjusting screw 34 which extends through the upper side wall of the casing 6. Said adjusting screw 34 is in engagement with the nut 35, which 30 is provided with a handle 36 by which it may be turned to vary the stress upon said spring and in consequence upon the lever 20. Such adjustment is effected by axial movement of said screw 34 without rotation thereof when said handle 36 is turned manually. Said screw 34 carries the pin 37 which actuates an indicating device by which the operator can determine the air pressure to be delivered to the tire, or other receiver, by the aforesaid adjustment of the screw 34 by 35 means of rotation of the handle 36. Such in-

dicating device is of the well known construction and includes an indicating hand which is caused to traverse a series of graduations on a dial face.

The outer end 40 of the shut-off valve 5 is provided with the eye 41 which is pivotally connected by the link 42 to the trip lever 43 which is fulcrumed on a stud 45 which projects from the casing 6. The upper end of said lever 43 is provided with the opening 46 for loose engagement with the pin 47 carried by the cam link 50. Said cam link 50, as is fully described in said Penn Patent Re. 19,201, is provided at its free end with a V-shaped cam portion 50' which is in engagement with a roller 51 carried by the stud 51' on the lever 20. The inclined surface of the V-shaped portion 50' of said cam 50 is maintained in engagement with the roller 51 by means of the spring 52, the upper end of which is connected to the cam link 50 and the lower end of which encircles the stud 53 rigidly fixed in the casing 6. The purpose of such mechanism is to impart a snap action to the member 40, to open or close said valves 4 and 5 with a snap action. Such snap action mechanism is old and well known in the art and forms no part of our invention.

Referring to the form of our invention shown in Figs. 2 and 3; the air inlet port 2 is in communication with the outlet port 12 through the communicating passageway 56 controlled by the main valve 4 and safety shut-off piston valve 5. Said main valve 4 is stressed towards closed position on its valve seat 57 by means of the spring 58, one end of which is engaged in the recess 59 formed in the head 60 of the valve 4. The opposite end of said spring 58 is engaged in the recess 61 formed in the end of the screw plug 62 which is engaged in the screw threaded opening 63 formed at the left-hand side of the casing 3. Said valve 4 is provided with the intermediate reduced stem portion 65 which is of lesser diameter than the diameter of the passageway 56. Said reduced portion 65 is of such length as to assure that the reduced portion 65 will be presented across the passageway 56 regardless of whether the valve 4 be in closed position as shown in Fig. 2 or in open position as shown in Fig. 3. The right-hand end 67 of said valve 4 is enlarged and is in sliding engagement in the guide opening 68 formed in said casing 3.

The safety shut-off piston valve 5 is in sliding engagement in the guide opening 68 and the left-hand end of said valve 5 is adapted to engage the right-hand end 67 of the main valve 4 and to move the main valve 4 to open position, as shown in Fig. 3, when said valve 5 is moved to open position by the snap mechanism. Said valve 5 is provided with the intermediate reduced portion 70 which is of lesser diameter than the diameter of the passageway 56. Said reduced portion 70 is arranged to be presented across the passageway 56 when the valve 5 is moved to open position, as shown in Fig. 3, so as to permit communication between the passageway 56 and the outlet port 12. The right-hand end of the valve 5 and the portion 40 thereof are fitted in sliding engagement in the guide passageway 72 formed in the screw threaded extension 10 of the casing 3.

When the snap action mechanism has moved the valve 5 from the position shown in Fig. 2 to the position shown in Fig. 3, the left-hand end of the valve 5 has engaged the right-hand end 67 of the valve 4 and moved the valve 4 to open position as shown in Fig. 3. When in such posi-

tion, the air under high pressure can flow through the inlet port 2, around the valve 4, through the valve seat 57, around the reduced portion 65 of the valve 4 to the passageway 56, and around the reduced portion 70 of the shut-off valve 5 to the outlet port 12, and thence to the conduit 13, etc.

The form of our invention shown in Figs. 4 and 5 is a modification of the structure shown in Figs. 2 and 3, and the casing 103 is arranged to be mounted in the wall of the casing 6 in the same manner as heretofore described with reference to the casing 3. Referring to Figs. 4 and 5; the air inlet port 102 is in communication with the air outlet port 112 through the communicating passageway 156 controlled by the main valve 104 and safety shut-off valve 105. Said main valve 104 is stressed towards closed position on its valve seat 157 by means of the spring 158, one end of which is engaged in the recess 159 formed in the head 160 of the valve 104. The opposite end of said spring 158 is engaged in the recess 161 formed in the end of the screw plug 162 which is engaged in the screw threaded opening 163 formed at the left-hand side of the casing 103.

Said valve 104 is provided with the intermediate reduced stem portion 165 which is of lesser diameter than the diameter of the passageway 156. Said reduced portion 165 is of such length as to assure that the reduced portion 165 will be presented across the passageway 156 regardless of whether the valve 104 be in closed position as shown in Fig. 4 or in open position as shown in Fig. 5. The right-hand end 167 of said valve 104 is enlarged and is in sliding engagement in the guide opening 168 formed in said casing 103.

The safety shut-off valve 105 is fitted in sliding engagement in the guide opening 168 and said valve 105 is provided with the guide rod 170 of reduced diameter, and the left-hand end of which is arranged to engage the recess 171 formed in the right-hand end of the valve 104 and to move the valve 104 to open position as shown in Fig. 5. The left-hand end of the guide rod 170 is slidably mounted in the guide washer 172 which is mounted rigidly in the opening 168 by means of the pin 173. The spring 175 encircles the guide rod 170, and the left-hand end of said spring 175 is in engagement with the guide washer 172. The right-hand end of said spring 175 is in engagement with the shoulder 176 formed on the valve 105.

The right-hand end of the casing 103 is provided with the screw threaded extension 110, similar to the extension 10 of the casing 3. The extension 110 is provided with the opening 178 for the packing 180, packing gland nut 181, and the stop guide member 182 for the push rod 140 which is of lesser diameter than the diameter of the passageway 156. A reduced diameter push rod and a stuffing box are used to limit the friction, and also to minimize the unbalanced air pressure which might occur when a push rod of larger diameter is used. The left-hand end of the push rod 140 is engaged in the socket 183 formed in the right-hand end of the shut-off valve 105. The right-hand end of the push rod 140 is provided with the eye 141 which is adapted to be pivotally connected to the link 42 in the same manner as has been heretofore described with reference to the eye 41 of the form of our invention shown in Figs. 2 and 3.

When the snap action mechanism has moved the valve 105 from the position shown in Fig. 4

to the position shown in Fig. 5, the left-hand end of the push rod 140 has engaged the end of the socket 183 in the safety valve 105 and moved the safety valve 105 from the position shown in Fig. 4 to the position shown in Fig. 5. Such movement of the valve 105 causes the end of the guide rod 170 of the valve 105 to engage the end of the socket 171 formed in the valve 104 and causes the main valve 104 to move from the position shown in Fig. 4 to the position shown in Fig. 5, and such movement has caused the spring 175, encircling the guide rod 170, to be compressed. When the main valve 104 and the safety shut-off valve 105 are in the open position as shown in Fig. 5, the air under high pressure can flow through the inlet port 102, around the valve 104, through the valve seat 157, around the reduced portion 165 of the valve 104 to the passageway 156, and around the push rod 140 to the outlet port 112, and thence to the conduit 13, etc. As shown in Fig. 5, when the valve 105 is in open position it has been moved from its closing position across the passageway 156, and the push rod 140 of lesser diameter is presented across the air passageway 156, so as to permit communication between the passageway 156 and the outlet port 112.

The left-hand end of the valve 105 is provided with the opening 190 which affords open communication between the socket 183 formed in the valve 105 and the guide passageway 168. The opening 190 permits air to flow from the right end to the left end, and vice versa, as the valve is being operated. It is to be noted that there should be an adequate amount of clearance around the push rod and through the opening to prevent entrapping of air, which would occur particularly as the valve 105 moves towards the right in Fig. 4 until arrested by the stop guide member 182.

The form of our invention shown in Figs. 6 and 7 is a modification of the structure shown in Figs. 2 and 3, and the casing 203 is arranged to be mounted in the wall of the casing 6 in the same manner as heretofore described with reference to the casing 3. In the structure shown in Figs. 6 and 7 a stuffing box and smaller push rod are used so as to limit the friction, and also to minimize the unbalanced air pressure which might occur on a push rod of large diameter. Referring to Figs. 6 and 7, the air inlet port 202 is in communication with the air outlet port 212 through the communicating passageway 256 controlled by the main valve 204 and the safety shut-off valve 205. Said main valve 204 is stressed towards closed position on its valve seat 257 by means of the spring 258, one end of which is engaged in the recess 259 formed in the head 260 of the valve 204. The opposite end of said spring 258 is engaged in the recess 261 formed in the end of the screw plug 262 which is engaged in the screw threaded opening 263 formed at the left-hand side of the casing 203. Said valve 204 is provided with the intermediate reduced stem portion 265 which is of lesser diameter than the diameter of the passageway 256. Said reduced portion 265 is of such length as to assure that the reduced portion 265 will be presented across the passageway 256 regardless of whether the valve 204 be in closed position as shown in Fig. 6 or in open position as shown in Fig. 7. The right-hand end 267 of said valve 204 is enlarged and is in sliding engagement in the guide opening 268 formed in said casing 203.

The safety shut-off valve 205 is fitted in sliding engagement in the guide opening 268. Said

valve 205 is mounted on the left-hand end of the push rod 240 which is of lesser diameter than the diameter of the valve 205 and of the diameter of the passageway 256. The right-hand end of the casing 203 is provided with the screw threaded extension 210, similar to the extension 10 of the casing 3. The extension 210 is provided with the packing 280, packing gland nut 281 and the guide member 282 for the push rod 240. The right-hand end of the push rod 240 is provided with the eye 241 which is adapted to be pivotally connected to the link 42 in the same manner as has been heretofore described with reference to the eye 41 of the form of our invention shown in Figs. 2 and 3.

The form of our invention shown in Figs. 6 and 7 functions in the same manner as the form of our invention shown in Figs. 2 and 3. When the main valve 204 and the safety shut-off valve 205 are in open position as shown in Fig. 7, the air under high pressure can flow through the inlet port 202, around the valve 204, through the valve seat 257, around the reduced portion 265 of the valve 204 to the passageway 256, and around the push rod 240 to the outlet port 212, and thence to the conduit 13, etc. As shown in Fig. 7, when the valve 205 is in open position it has been moved from its position across the passageway 256 and the reduced diameter push rod 240 is presented across the passageway 256, so as to permit communication between the passageway 256 and the outlet port 212.

Operation

The form of our tire inflating apparatus shown in Figs. 1, 2 and 3 operate as follows:

Assuming that it is desired to inflate an automobile tire to a pressure of 30 pounds per square inch, the operator turns the crank 36 to move the indicating hand to the numeral 30 appearing on the dial face. The operator then presses the air chuck 18 upon the stem of the automobile tire which opens the tire valve and likewise moves the valve in the air chuck to open position against the air pressure in the hose 17. If the pressure in the tire is below the set pressure of 30 pounds, the air under higher pressure in the hose 17, conduit 16, air chamber in the member 30 beneath the diaphragm 26, and conduit 13 tends to equalize with the pressure in the tire, thereby reducing the pressure in the chamber beneath the diaphragm 26. When the pressure in the diaphragm chamber is reduced to a point where such pressure no longer can overcome the effective forces of the spring 32, the spring 32 moves the lever 20 counter-clockwise. Such counter-clockwise movement of the lever 20 moves the roller 51 beneath the crest of the V-shaped cam portion 50' of the cam link 50 and the spring 52 causes the cam link 50 to move downwardly and to the right with a snap action. Such snap action is transmitted from the cam link 50 to the lever 43, thus imparting a snap action movement to the link 42, thereby causing the safety shut-off valve to be moved from the position shown in Fig. 2 to the position shown in Fig. 3. The operation of such snap action linkage construction is old in the art and disclosed in detail in Penn Patent Re. 19,201.

When the safety shut-off valve 5 is moved from the position shown in Fig. 2 to the position shown in Fig. 3, the reduced portion 70 of the lesser diameter of the passageway 56 is presented across the passageway 56 so as to permit communication between the passageway 56 and the outlet

port 12. Such movement of the safety shut-off valve 5 from the closed position shown in Fig. 2 to the open position shown in Fig. 3 causes the left-hand end of the valve 5 to engage the right-hand end of the main valve 4 and moves the main valve 4 from closed position to open position.

With the main inflating valve 4 thus open, air under pressure from the source flows through the air inlet port 2, around the valve 4, through the valve seat 57, around the reduced portion 65 of the valve 4 to the passageway 56, around the reduced portion 70 of the shut-off valve 5 to the outlet port 12, through the conduit 13 to the T-fitting 15, conduit 16, dispensing hose 17, opened air chuck 18 and thence to the automobile tire through the open valve thereof. A restricted amount of high pressure air is admitted to the chamber in the casing 30 through the timer valve in the branch 15' of the T-fitting 15. Because the air under high pressure is admitted slowly to the chamber beneath the diaphragm 26 through the timer valve, approximately one or two pounds of air is supplied to the tire before the pressure in the diaphragm chamber becomes great enough to cause the diaphragm to move the stud 25 upwardly to cause the lever 20 to move clockwise against the effective forces of the spring 32. Movement of the lever 20 clockwise causes the snap action mechanism to move the shut-off valve 5 from the position shown in Fig. 3 to the position shown in Fig. 2 and wherein the shut-off valve 5 closes the passageway 56 and prevents further flow of air through the air outlet 12 to the tire. Movement of the shut-off valve 5 from the position shown in Fig. 3 to the position shown in Fig. 2, permits the main valve 4 to be snapped to closed position by the effective forces of its spring 58.

If the main valve 4 should fail to seat for any reason, such as a particle of foreign matter on the valve 4 or the valve seat 57, or because of the breaking of the spring 58, air could not continue to flow through the mechanism from the supply tank because the safety shut-off valve 5, connected directly to the snap mechanism, has been moved positively to closed position across the air passageway 56, thereby preventing any further flow of air.

The forms of our invention shown in Figs. 4 to 7 inclusive function in the same general manner.

Although we have described our invention in connection with fluid dispensing apparatus wherein the main inflating valve is pushed from its seat to open said valve, it is obvious that our invention also is adaptable to fluid dispensing apparatus wherein the main inflating valve is pulled off its seat. Accordingly, it is obvious that various modifications may be made in our invention without departing from the essential features thereof as defined in the appended claims and, therefore, we do not desire to limit ourselves to the precise details of construction and arrangement hereinabove set forth.

We claim:

1. In fluid dispensing apparatus for filling a receiver with air in pulsations to a predetermined pressure; the combination of an inlet conduit adapted for connection with a source of supply of air under pressure; an outlet conduit adapted for connection with a receiver; conduit means connecting said inlet and outlet conduits; pressure regulating mechanism; a main inflating valve between said inlet conduit and said outlet conduit; a snap action mechanism operatively

connected to said pressure regulating mechanism; a safety shut-off valve between said inlet conduit and said outlet conduit and arranged to operate said main inflating valve; and means operatively connecting said safety shut-off valve directly with said snap action mechanism.

2. In fluid dispensing apparatus for filling a receiver with air in pulsations to a predetermined pressure; the combination of an inlet conduit adapted for connection with a source of supply of air under pressure; an outlet conduit adapted for connection with a receiver; conduit means connecting said inlet and outlet conduits; pressure regulating mechanism; a main inflating valve between said inlet conduit and said outlet conduit; a snap action mechanism operatively connected to said pressure regulating mechanism; a safety shut-off valve between said inlet conduit and said outlet conduit and arranged to operate said main inflating valve; and means connecting said safety shut-off valve directly to said snap action mechanism to actuate said safety shut-off valve positively by said snap action mechanism.

3. In fluid dispensing apparatus for filling a receiver with air in pulsations to a predetermined pressure; the combination of an inlet conduit adapted for connection with a source of supply of air under pressure; and outlet conduit adapted for connection with a receiver; conduit means connecting said inlet and outlet conduits; pressure regulating mechanism; a main inflating valve between said inlet conduit and said outlet conduit; a snap action mechanism operatively connected to said pressure regulating mechanism; a safety shut-off valve between said main inflating valve and said outlet conduit and arranged to operate said main inflating valve; and means operatively connecting said safety shut-off valve directly to said snap action mechanism.

4. In fluid dispensing apparatus for filling a receiver with air in pulsations to a predetermined pressure; the combination of an inlet conduit adapted for connection with a source of supply of air under pressure; an outlet conduit adapted for connection with a receiver; conduit means connecting said inlet and outlet conduits; pressure regulating mechanism; a main inflating valve between said inlet conduit and said outlet conduit; a snap action mechanism operatively connected to said pressure regulating mechanism; a safety shut-off valve between said inlet conduit and said outlet conduit and arranged to operate said main inflating valve; means tending to move said safety shut-off valve towards closed position; and means operatively connecting said safety shut-off valve directly to said snap action mechanism.

5. In fluid dispensing apparatus for filling a receiver with air in pulsations to a predetermined pressure; the combination of an inlet conduit adapted for connection with a source of supply of air under pressure; an outlet conduit adapted for connection with a receiver; conduit means connecting said inlet and outlet conduits; pressure regulating mechanism; a main inflating valve between said inlet conduit and said outlet conduit; a snap action mechanism operatively connected to said pressure regulating mechanism; a safety shut-off valve between said inlet conduit and said outlet conduit and arranged to operate said main inflating valve; spring means tending to move said safety shut-off valve toward closed position; and means operatively connecting

said safety shut-off valve directly to said snap action mechanism.

6. In fluid dispensing apparatus for filling a receiver with air in pulsations to a predetermined pressure; the combination of an inlet conduit adapted for connection with a source of supply of air under pressure; an outlet conduit adapted for connection with a receiver; conduit means connecting said inlet and outlet conduits; pressure regulating mechanism; a main inflating valve between said inlet conduit and said outlet conduit; a snap action mechanism operatively connected to said pressure regulating mechanism; a safety shut-off valve between said inlet conduit and said outlet conduit; means operatively connecting said safety shut-off valve directly to said snap action mechanism; and means connected to said safety shut-off valve and arranged to operate said main inflating valve.

7. A structure as in claim 1; wherein the safety shut-off valve is provided with a reduced diameter portion of lesser diameter than the diameter of the safety shut-off valve; whereby said reduced diameter portion is presented across said conduit means connecting said inlet and outlet conduits when said safety shut-off valve is moved to open position by said snap action mechanism.

8. A structure as in claim 1; wherein the safety shut-off valve is provided with a push rod of lesser diameter than the diameter of the safety shut-off valve; whereby said push rod is presented across said conduit means connecting said inlet and outlet conduits when said safety shut-off valve is moved to open position by said snap action mechanism.

9. In fluid dispensing apparatus for filling a receiver with air in pulsations to a predetermined pressure; the combination of an inlet conduit adapted for connection with a source of supply of air under pressure; an outlet conduit adapted for connection with a receiver; conduit means connecting said inlet and outlet conduits; pressure regulating mechanism; a main inflating valve between said inlet conduit and said outlet conduit; means operatively connected to said pressure regulating mechanism to cause quick opening or closing of the said main valve; and a safety shut-off valve, connected directly to said means for causing quick opening or closing of said main valve, between said inlet and said outlet conduits; whereby, said last mentioned means is in controlling relation to said main valve and said safety shut-off valve.

10. In fluid dispensing apparatus for filling a receiver with air in pulsations to a predetermined

pressure; the combination of an inlet conduit adapted for connection with a source of supply of air under pressure; an outlet conduit adapted for connection with a receiver; conduit means connecting said inlet and outlet conduits; pressure regulating mechanism; a main inflating valve between said inlet conduit and said outlet conduit; a snap action mechanism operatively connected to said pressure regulating mechanism; a safety shut-off valve between said inlet conduit and said outlet conduit and connected directly to said snap action mechanism; and means operatively connecting said main valve and said safety shut-off valve with said snap action mechanism.

11. In fluid dispensing apparatus for filling a receiver with air in pulsations to a predetermined pressure; the combination of an inlet conduit adapted for connection with a source of supply of air under pressure; an outlet conduit adapted for connection with a receiver; conduit means connecting said inlet and outlet conduits; pressure regulating mechanism; a main inflating valve between said inlet conduit and said outlet conduit; a snap action mechanism operatively connected to said pressure regulating mechanism; a safety shut-off valve between said inlet conduit and said outlet conduit and connected directly to said snap action mechanism; and means adapted to operate said main valve by said safety shut-off valve connected with said snap action mechanism movement.
